UNITED STATES PATENT OFFICE.

LOUIS STREBEL, OF NEW YORK, N. Y.

MOTOR-VALVE.

1,380,435.

Specification of Letters Patent.

Patented June 7, 1921.

Application filed February 16, 1917. Serial No. 149,142.

To all whom it may concern:

Be it known that I, LOUIS STREBEL, a citizen of the United States, and resident of New York, in the county of New York and State of New York, have invented certain new and useful Improvements in Motor-Valves, of which the following is a specification.

This invention relates essentially to a single valve with two passageways which is operated by means of a crank shaft connected to a piston adapted to reciprocate in a cylinder.

The object of the invention is to provide the valve with means for dividing it into a plurality of winding compartments to control the intake and exhaust.

Another object of the invention is to provide a fuel compartment supporting one end of the valve adapted to permit expansion and warming of the combustible before it is admitted into the valve compartment.

The invention is designed to provide a single intake in the cylinder for admitting the combustible, which also serves as an outlet for the products of combustion.

The valve being operated to rotate by means of the crank shaft, positively opens or closes the intake and exhaust when desired, thus opening and closing the port in each cylinder at any speed of the crank shaft.

The invention is especially adapted for a four cycle explosive motor comprehending a series of cylinders, the fuel mixture being admitted on one side of the valve, while the other side of the valve after the explosion will connect with the exhaust for conducting the products of combustion.

The novel features of the invention are more fully described in the following specification and claim, and illustrated in the accompanying drawings in which:

Fig. 1 represents a vertical section of a motor embodying this invention.

Fig. 2 is a horizontal longitudinal section of the valve and its casing.

Fig. 3 is a longitudinal section of the valve.

Fig. 4 is an end view of the valve and casing showing the intake.

Fig. 5 is a similar view showing the exhaust end of the valve and casing.

Fig. 6 is a diagram showing the successive cycles of the motor.

In the drawings is shown an explosive engine or motor having a series of cylinders *a* coupled together, each provided with a piston *b* made to reciprocate in the cylinder 60 by the explosion of a combustible as is well known. The pistons are connected by means of rods *c* to the cranks *d* of a driving shaft *e* mounted to rotate in bearings *f* extending from the lower portions of the cylinders. A water jacket *g* is provided for cooling the cylinders.

Mounted on the cylinders is a cylindrical casing *h* having a bore *i* open at each end. A water jacket *i'* is made to cool the casing. The casing is provided with a plurality of ports *j* for connecting the interior of each cylinder *a* with the bore of the casing, the function of which will be hereinafter described.

A valve *k* is arranged in the bore of the casing, and it has packing rings *m* to prevent leakage of the fluid between the bore and casing. This valve can be tubular as shown or it could be cylindrical with the 80 intake and exhaust ports formed in the periphery of the valve. A series of intake ports *n* and exhaust ports *o* are formed in the shell of the valve and coact at predetermined times with the ports *j* in the casing *h* communicating with the cylinders.

A convoluted partition *p* divides the valve *k* into two compartments *q* and *r* the former being adapted to lead off the products of combustion while the latter constitutes the 90 intake for the combustible mixture. An exhaust pipe *s* is fitted to a cover *t* and bolted to the rear end of the casing. The rear end of the convoluted partition of the combustible compartment, is cut off from 95 the exhaust by means of a wall *u* disposed transversely, as indicated in Fig. 3. The forward end of the valve has a combustible intake opening *v* leading to the fuel compartment. A cover *w* having a double wall 100 is bolted to the forward end of the casing. This cover has a circular opening *x* located in the inner wall and a pipe *y* connected to a carburetor will draw the combustible into the fuel compartment of the 105 valve.

From the forward end of the valve projects a journal *z* and a stuffing box 115 mounted on the outer wall of the cover coacting with the journal will obviate leakage of 110 the fluid. The journal has secured to it a gear 16 which meshes with a gear 17 mount-

ed on a shaft 18 secured to the cylinder. The latter gear is actuated by means of a pinion 19 fastened to the crank shaft and made to mesh with a gear 20 secured to the gear 17. Through the medium of this train of gears two revolutions of the crank shaft will transmit one revolution to the valve *k*, thereby governing it to open or close the port in the cylinder at the proper time.

10 As indicated in Figs. 2 and 3 the convolutions of the partition *p* of the valve *k* form winding or tortuous passages in the valve to control the intake and exhaust of the four cylinders. The passages permit 15 the first cylinder to explode the combustible, the second to compress, the third to exhaust and the fourth to intake the combustible mixture. Each cylinder has a single port 20 and coöperating with the valve *k* to at times intake the combustible, and at other times perform the function of exhausting the products of combustion after the explosion. The valve can be made to control any 25 number of cylinders, and by its peculiar formation one port in each cylinder is sufficient for coaction with the valve, thus minimizing clogging of valve and subsequent fracture of the parts.

30 As indicated in Fig. 6 the four figures from top to bottom illustrate the four successive strokes of the motor. The position of the various pistons and their relation to each other when the front cylinder is about 35 to fire is shown in the upper figure. The pistons move downward during the explosion and intake strokes and they move upward during the compression and exhaust strokes. In this arrangement the front cylinder 40 fires first, then the second cylinder, then the fourth cylinder, and lastly the third cylinder. The four operations of the cycle namely, suction, compression, explo-

sion and exhaust are repeated in regular order in each of the four cylinders according to the firing order. When the first piston is at the top of its stroke with the fuel above it fully compressed and ready for ignition, the second piston is at the bottom of the suction stroke just at the beginning 50 of its compression stroke and the valve *k* coöperating with the ports *j* in both cylinders is closed. When the piston in the third cylinder starts moving up on its exhaust stroke, it will force the products of combustion out of the cylinder through the passageway *g* of the valve *k*. The piston in the fourth cylinder is then moving downward and as the intake passageway *r* is adjacent to the port *j* it permits a charge of gas to be 55 drawn into the cylinder from the carburetor.

It will be readily understood, that the valve with its two passageways could be utilized for governing the port of a hydraulic as well as pneumatic or any other 60 fluid controlled engine.

I claim:—

An explosive motor comprising a series of cylinders each having a port controlling the intake and exhaust, a tubular rotary valve 70 having inlet and exhaust to coöperate with the cylinder ports, a fuel compartment having an inner and outer wall located adjacent the inlet, the outer wall being made to support the axis of the valve, a circular inlet disposed in the other wall for admitting a combustible into the valve, and a cover 75 having an exhaust outlet fixed opposite to the compartment.

Signed at New York, in the county of 80 New York and State of New York, this 14th day of February, A. D. 1917.

LOUIS STREBEL.
